UNITED STATES PATENT OFFICE.

MATTHEW T. CHAPMAN AND MARK C. CHAPMAN, OF AURORA, ILLINOIS, ASSIGNEES TO THE AMERICAN WELL WORKS, OF AURORA, ILLINOIS, A CORPORATION OF ILLINOIS.

PUMPING MACHINERY.

1,152,603.

Specification of Letters Patent.

Patented Sept. 7, 1915.

Application filed November 21, 1910. Serial No. 593,470.

To all whom it may concern:

Be it known that we, MATTHEW T. CHAPMAN and MARK C. CHAPMAN, citizens of the United States, residing at Aurora, in the county of Kane and State of Illinois, have invented certain new and useful Improvements in Pumping Machinery, of which the following is a specification, reference being had to the accompanying drawings.

10 Our invention relates to pumping machinery for deep-well pumps, and has particularly to do with pumping machinery of the type shown and described in our pending application Serial No. 561,587, filed 15 May 16, 1910, in which the pump-rod is reciprocated by a pair of cranks carried by intermeshing gears so that they operate in unison to reciprocate the pump-rod without side-draft, and make it practicable to 20 secure a longer stroke, by which a greater quantity of water can be raised than with a short stroke.

The object of our invention is to provide certain improvements upon the pumping 25 machinery shown and described in our said application,—such improvements relating more particularly to the connection between the driving gears and the pump-rod and piston, by which the construction is simplified and strengthened and a smoother action secured. We accomplish this object as illustrated in the drawings and as hereinafter described.

What we regard as new is set forth in the 25 claims.

In the accompanying drawings,—Figure 1 is an elevation of the pump operating mechanism; Fig. 2 is a plan view thereof; Fig. 3 is an enlarged detail, being a partial 40 vertical section on line 3—3 of Fig. 2; Fig. 4 is a similar view, being a section on line 4—4 of Fig. 3; Fig. 5 is an end view of the axis of the hub of one of the driving gears and showing the drum connected therewith 45 for hoisting purposes; Fig. 6 is a plan view of the parts shown in Fig. 5; Fig. 7 is a detail, being a partial vertical section on line 7—7 of Fig. 1; Fig. 8 is an enlarged detail, being a section on line 8—8 of Fig. 50 7; Fig. 9 is a perspective view of the stirrups used in connection with the cross-head and the guides therefor; Fig. 10 is a vertical section illustrating the bearing plates by 55 which the pump-rod is secured against rotation and is permitted to oscillate slightly;

and Figs. 11 and 12 are partial side views showing modified arrangements of the driving mechanism.

Referring to the drawings,—11 indicates the base which supports various parts of the 60 mechanism.

12 indicates the piston or pump rod which rises through the base 11 and is connected at its lower end with a pump-rod 13 which extends down into the well and is provided 65 with a piston in the usual way. Such a piston is shown and described in the pending application of Matthew T. Chapman Serial No. 426,556, filed April 11, 1908. The construction of the piston, however, has 70 nothing to do with our present invention, as any suitable piston may be employed.

14 indicates the well-tube, which is preferably connected with the base 11 and is provided with an outlet 15 for the discharge of 75 the water.

16—17 indicate uprights or standards which rise from the base 11 and are connected at their upper ends by a cross-brace 18, as shown in Fig. 1. The brace 18 is provided with a central passage for the passage 80 of the end of the piston-rod when the latter is raised to its uppermost position, as shown at 19 in Figs. 1 and 2. The brace 18 is held in position by set-screws 20 so that it may 85 be conveniently removed when desired to permit of the removal of the cross-head hereinafter described.

21—22 indicate upper and lower beams or bars, which are mounted upon the uprights 90 16—17 and are spaced a distance apart so as to form a cross-head having a transverse groove or guide, as shown in Fig. 1. Said bars are spaced apart by means of stirrups 23 fitted between them and embracing the 95 uprights 16—17, as shown in Figs. 1, 7 and 8. The end portions of the bars 21—22 are secured together by bolts 24, which also serve to hold the stirrups 23 in position, the ends of the stirrups being bent inward 100 slightly, as shown in Fig. 7, so that they cannot get out of place. 25 indicates bolts which secure the intermediate portions of the bars 21—22 together, as shown in Fig. 1,—said bolts being so disposed as not to be 105 in the way.

26—27 indicate driving-wheels in the form of gears mounted upon parallel drive-shafts 28—29, respectively, which are suitably journaled upon the base 11, as shown in Fig. 110

2, 30—31 indicating supports for said shafts. The gears 26—27 rotate in unison in opposite directions, and in the construction shown in Figs. 1, 2 and 11 they intermesh, while in the construction shown in Fig. 12 they are set a distance apart. 32—33 indicate slide-blocks connected, respectively, with the drive-wheels 26—27 by wrist-pins 34—35, said slide-blocks being arranged to slide in the ways formed by the bars 21—22 of the cross-head. Obviously, by this construction when the drive-wheels 26—27 rotate, the slide-blocks 32—33 will move in opposite directions in the cross-head guideway and will raise and lower the cross-head, which will move upon the posts 16—17.

In the arrangement shown in Figs. 1 and 2 the drive-wheels 26—27 are driven by means of a motor 36 mounted on the base and connected by a pinion 37 with a gear 38, which is mounted on a shaft 39, as best shown in Fig. 2. Said shaft 39 carries a pinion 40 which meshes with the gear 26 at 25 the lower inner margin thereof and also meshes with a pinion 41 mounted on a counter-shaft 42 arranged parallel with and adjacent to the shaft 39, as shown in Fig. 2. The pinion 41 meshes with the gear 27 as 30 well as with the pinion 40 so that power is applied directly to both drive-wheels 26—27. Instead of employing the two pinions 40—41, we may employ a single pinion meshing with one or the other of the drive-wheels 26—27, as shown in Fig. 11, wherein the pinion 40 meshes with drive-wheel 26, the latter meshing with drive-wheel 27, power being communicated to said drive-wheel 27 in that way; or, if desired, the 35 drive-wheels may be set a distance apart so that they do not intermesh, as illustrated in Fig. 12, the pinions 40—41 being employed to communicate the power to said drive-wheels.

43 indicate counterbalancing weights secured upon the shafts 28—29 to counterbalance the weight of the pump-rod and of the water being lifted.

44 indicates a drum mounted upon one 50 end of the shaft 28 and rotating therewith, as indicated by dotted lines in Fig. 2 and shown in full lines in Fig. 6. The drum 44 provides convenient means for hoisting the pump-rod, or for any other desired use.

55 The pump-rod 12 is connected with the cross-head by means of bearing-plates 45—46 which are semi-cylindrical so as to fit together around the pump-rod and are provided with trunnions 47—48 which fit in 60 suitable bearing-blocks 49—50 carried by the cross-head bars 21—22 and preferably formed integral therewith, as shown in Figs. 1 and 3, the engagement of the oppositely-disposed semi-cylindrical trunnion members 65 of the separate bearing plates 45—46 with

the bearings of the blocks 49—50 serving to hold the lower ends of the said bearing plates together about the pump-rod. The cross-head bars 21—22 are provided with registering vertical passages to receive said bearing-plates, said passages being conical in form so as to permit of some oscillation of the piston-rod, as may be necessary to allow it to compensate for disarrangement of the position of the lower portion of the pump-rod, as when said pump-rod gets somewhat out of line. The bearing-plates 45—46 are internally serrated or screw-threaded to engage the pump-rod more firmly, said rod being also screw-threaded or roughened. A collar 51 is fitted upon the upper ends of the bearing-plates 45—46 and is secured thereto by a set-screw 52, as shown in Fig. 4,—said collar resting upon the upper cross-head bar 21. The purpose 85 of this collar is to clamp the bearing plates 45—46 upon the pump-rod and hold it against rotation.

53 indicates a nut screwed upon the pump-rod 12 above the collar 51 for suspending the pump-rod from the cross-head. By adjusting the nut 53 the piston may be adjusted vertically in the pump cylinder. The bolts 25 are placed at opposite sides of the bearing-blocks 49—50 so as to properly clamp the bearing-blocks down upon the trunnions 47—48, as shown in Figs. 1 and 3.

From the foregoing description it will be seen that when the gears 26—27 are rotated, the cross-head will be caused to travel vertically upon the guide posts 16—17, thereby operating the pump, and as the slide-blocks 32—33 are always equidistant from the pump-rod the operation of the pump is free from side friction. Moreover, the upper end of the pump-rod is free to accommodate itself to the lateral movement of the lower portion of the piston or pump-rod so that there is no binding.

That which we claim as our invention, and desire to secure by Letters Patent, is,—

1. In a pump, the combination of a pump-rod, a cross-head, oscillating means connecting said pump-rod with said cross-head comprising semi-cylindrical bearing-plates having trunnions journaled in the cross-head, said cross-head having a conical passage to receive said bearing-plates, and means for reciprocating said cross-head.

2. In a pump, the combination of a pump-rod, a cross-head, means for reciprocating said crosshead, and means for connecting said crosshead to said pump-rod, said connecting means comprising bearing plates pivotally mounted on said crosshead and embracing said pump-rod, and means for tightening said bearing plates in position about the pump-rod in adjusted position thereon.

3. In a pump, the combination of a pump-rod, a cross-head, means for reciprocating said cross-head, and means for connecting said crosshead to said pump-rod, said connecting means comprising bearing plates pivotally mounted on said crosshead and embracing said pump-rod, a collar about said bearing plates, and a set-screw mounted in said collar adapted to tighten said bearing plates together about said pump rod, said rod and said bearing plates having their contact faces roughened whereby secure clamping is attained.
4. In a pump, the combination of a pump-rod, a cross-head, means for reciprocating said cross-head, and means for connecting said cross-head to said pump-rod, said connecting means comprising two bearing plates adapted to embrace said pump-rod, trunnion members carried by each of said plates adapted to coöperate with the trunnion members of the other plate, bearings carried by said cross-head in which said trunnions are journaled, and other means for tightening said bearing plates in position about the pump-rod.
5. In a pump, the combination of a pump-rod, a cross-head, means for reciprocating said cross-head, and means for connecting said cross-head to said pump-rod, said connecting means comprising two bearing plates adapted to embrace said pump-rod, trunnion members carried by each of said plates adapted to coöperate with the trunnion members of the other plate, bearings carried by said cross-head in which said trunnions are journaled and which are adapted to be tightened about the trunnion members for holding said bearing plates together about the pump-rod, and other means for tightening said bearing plates in position about the pump-rod.
6. In a pump, the combination of a pump-
- rod, a cross-head, means for reciprocating said cross-head, and means for connecting said cross-head to said pump-rod, said connecting means comprising two bearing plates adapted to embrace said pump-rod, trunnion members formed with each of said bearing plates and extending from the lower end thereof, the trunnion members of each bearing plate being adapted to coöperate with the trunnion members of the other bearing plate, bearings carried by said cross-head in which said trunnions are journaled and which are adapted to be tightened about the trunnion members for holding their lower ends together about the pump-rod, and means for tightening the upper ends of said bearing plates together about the pump-rod.
7. In a pump, the combination of a pump-rod, a cross-head in the form of two bars spaced one above the other, means for reciprocating said cross-head, and means for connecting said cross-head to said pump-rod, said connecting means comprising two bearing plates adapted to embrace said pump-rod, trunnion members carried by each of said plates adapted to coöperate with the trunnion members of the other plate, oppositely-disposed bearing blocks carried by the cross-bars of said cross-head adapted to provide bearings for said trunnions, means for tightening said bearing blocks together for tightening the bearings about the trunnions and for holding the lower ends of the bearing plates together about the pump-rod, and other means for tightening said bearing plates in position about the pump-rod.
